Davis & Summ
his ATTORNEYS.

UNITED STATES PATENT OFFICE.

GEORGE R. McALLASTER, OF ROCHESTER, NEW YORK.

FOLDING BED.

1,344,450.

Specification of Letters Patent. Patented June 22, 1920.

Application filed December 28, 1918. Serial No. 268,741.

To all whom it may concern:

Be it known that I, GEORGE R. McALLASTER, a citizen of the United States, and resident of Rochester, in the county of 5 Monroe and State of New York, have invented certain new and useful Improvements in Folding Beds, of which the following is a specification.

The present invention relates to folding 10 beds and more particularly to the type in which a bed frame is movable upon a suitable support to an upright position in order that the bed may be compactly arranged in a room when not in use, an object of this 15 invention being to provide a means for holding the mattress to the bed frame when the latter is upright, such means being of simple construction so that it may be readily operated by one unskilled with mechanical 20 structures and the means also being so constructed and arranged that it will not make the occupancy of the bed uncomfortable.

To these and other ends the invention 25 consists of certain parts and combinations 30 of parts all of which will be hereinafter described, the novel features being pointed out in the appended claims.

In the drawings:—

Figure 1 is a side view of a bed in which 35 the bed frame is thrown to an upright position and the present invention is embodied therein;

Fig. 2 is a fragmentary view of the swinging 40 end of the bed frame in a lowered position;

Fig. 3 is an enlarged end view of the swinging 45 end of the bed frame showing the mattress removed and the mattress-secur- and-sustaining means in position on the frame;

Fig. 4 is an enlarged fragmentary view of the mattress-secur- and-sustaining means showing its manner of attachment to the cross piece at the swinging end of the bed 50 frame;

Fig. 5 is a detail sectional view through the mattress-sustaining-and-secur- means;

Fig. 6 is a view similar to Fig. 5 of another embodiment of the invention in which 55 the base plate of the mattress-secur- and-sustaining means is arranged on the under side of the wire fabric.

Referring more particularly to the drawings, 1 indicates the base of a supporting member which has two uprights 2 rising therefrom and to which the side bars 3 of

the bed frame are pivoted at 4 in order that the bed frame may swing from a horizontal position or position of use shown in Fig. 2, to the upright or folded position shown 60 in Fig. 1.

The bed frame in this instance embodies in addition to the side bars 1 which are made of angle iron, a cross piece 5 at the foot or swinging end of the bed and a cross 65 piece 6 at the head or inner end of the bed, the cross piece 6 being supported on castings or blocks 7 which space such cross piece 6 from the side bars 3 so that the fabric 8 which connects the cross pieces 5 and 6 will 70 have its plane at a slight angle to the plane of the side bars 3. The blocks or spacing devices 7 support a transversely extending weight 9 which tends to counterbalance the foot end of the bed. No claim is made in 75 this application to this counterbalancing device nor to the spacing blocks 7 which produces the inclination of the fabric with reference to the side bars of the bed frame as these form the subject matter of other ap- 80 plications filed by me.

The feature of the invention is the sustaining-and-secur- means for the mattress 10. This sustaining-and-secur- means in this instance comprises a base member 11 85 preferably in the form of an elongated piece supported in this instance at the foot or swinging end of the bed frame. The supporting means therefor preferably embodies two hooks 12 fastened at 13 to the underside 90 of the base member and extending laterally from said base member so as to engage about the cross piece 5 at the foot of the bed. It is apparent that, when the bed frame is in its lowermost position, no strain will be 95 imposed on these hooks, but that when the bed frame is in an upright position as shown in Fig. 1, the hooks will sustain the base member 11 and the mattress. In the embodiment shown in Figs. 1 to 5 the base mem- 100 ber 11 rests upon the fabric 8 whereas in the embodiment shown in Fig. 6 the base member 11^a lies on the under side of the fabric 8 and the hooks 12^a are deflected in the manner shown in Fig. 6 so that such 105 hooks may engage about the cross piece 5.

The base member 11 is provided preferably along one edge with projecting means 14, this projecting means in this instance consisting of a bevel or knife edge extending 110 throughout the length of the base member 11, said edge being scalloped. In the em-

bodiment shown in Fig. 6, the projecting means is in the form of a number of projections 14^a, which may be passed through the fabric 8 in the manner shown. In both 5 embodiments, the projecting means will bite into the under side of the mattress 10 in the manner shown in Figs. 1 and 2, thus tending to retard the dropping of the mattress when the bed frame is thrown to the upright position shown in Fig. 1.

To hold the mattress in engagement with the projecting means, provision may be made for engaging the mattress on its upper side and transversely thereof to one side 15 of the projecting means, preferably, at a point between such projecting means and the foot of the bed. This engaging-and-holding means, in this instance, consists of a strap having two sections 15 and 16 each 20 secured at one end to the base member 11 as at 17, one of said strap sections having a buckle 18 at its free end for engagement with the free end of the other strap section so that the mattress may be held by the two 25 sections firmly against the base member 11 to one side of the projecting means 14.

With this arrangement, when the bed frame is thrown to the upright position as shown in Fig. 1, its upper or foot end will 30 firmly hold the mattress against slipping downwardly on the fabric 8. The lower end of the mattress will abut the weight 9 and the mattress will be bulged in the manner shown in Fig. 1 so that a turning or 35 working of the mattress after use will be unnecessary for the purpose of softening such mattress. The sustaining-and-holding means is a simple construction and may be readily manipulated by one unskilled in 40 mechanical structures, thus permitting the mattress to be readily detached from the bed or readily secured in position on such bed. The holding-and-sustaining means for the mattress is detachable from the bed 45 frame so that its use may be dispensed with if desired or it may be used in connection with other structures.

As the clamp engages the mattress at any 50 desired distance from the end of the mattress, it is possible to use mattresses of different lengths or to project the end of the mattress beyond the bed frame for tall people. Furthermore, the mattress may be so 55 adjusted with reference to the weight or head piece 9 that a desired bulging of the mattress may be obtained so as to work the mattress to soften the latter when the bed frame is thrown to an upright position.

What I claim as my invention and desire 60 to secure by Letters Patent is:—

1. In combination with a bed frame, and a mattress supported thereon, projecting means secured to the frame and engaging the under side of the mattress, and means 65 extending across the upper side of the mat-

tress from one side of the bed frame to the other and to one side of the projecting means to secure the mattress to the bed frame.

2. In combination with a bed frame, and 70 a mattress supported thereon, projecting means secured to the frame to engage the under side of the mattress, and flexible means mounted to extend across the upper side of the mattress to one side of the projecting means to secure the mattress to the bed frame, said flexible means having a provision to permit the removal of the mattress.

3. In combination with a bed frame, and 80 a mattress supported thereon, a base member extending transversely of the mattress on the under side thereof, means carried by said base member for detachably engaging the bed frame, and flexible means carried 85 by said base member for extending across the upper side of the mattress to secure said mattress to the bed frame.

4. In combination with a bed frame and a mattress supported thereon, a base member 90 extending transversely of the mattress on the under side thereof, means carried by said base member for securing the mattress thereto, and hooks on said base member detachably engaging with the cross bar of the 95 bed frame.

5. In combination with a bed frame, and 100 a mattress supported thereon, a base member extending transversely of the mattress on the under side thereof, projecting means on said base member for engaging the under side of the mattress, and means extending across the upper side of the mattress to one side of the projecting means to secure the 105 mattress to the bed frame.

6. In combination with a bed frame and a mattress supported thereon, a base member 110 extending transversely of the mattress on the under side thereof, projecting means arranged on said base member for engaging with the under side of the mattress, and flexible means carried by said base member extending across the upper side of the mattress to one side of the projecting means to 115 secure the mattress to the bed frame.

7. A mattress securing means comprising a base member, projecting means on said base member for engaging with the under side of the mattress, and flexible means on said base member for extending across the 120 upper side of the mattress to one side of the projecting means to secure the mattress to the bed frame.

8. A mattress securing and sustaining means comprising a rigid base member 125 adapted to be positioned between the mattress and the bed frame to coöperate with the under side of the mattress, hooks carried by said base member for detachably engaging with the foot of the bed, and 130

means connected to opposite ends of said base member for engaging the upper side of the mattress to secure the mattress to the bed frame.

- 5 9. A mattress sustaining and securing means comprising a base member, hooks carried by said base member for detachably engaging with the bed, projecting means on said base member for engaging the under 10 side of the mattress, and flexible means on said base member for extending across the upper side of the mattress to one side of the projecting means to secure the mattress to the bed frame.
- 15 10. A mattress securing and sustaining means comprising a rigid base member adapted to be positioned between the mattress and the bed frame to coöperate with

the under side of the mattress, hooks carried by said base member for detachably engaging the foot of the bed, and flexible means connected to opposite ends of the base member for engaging the upper side of the mattress to secure the mattress to the bed frame.

- 20 25 11. A mattress securing and sustaining means comprising a rigid base member having projecting portions for engaging the under side of a mattress, means for detachably securing said base member to a bed frame, and a flexible securing means connected to opposite ends of the base member for drawing the mattress in firm engagement with the projecting means on the base member.

GEORGE R. McALLASTER.
